MACHINE FOR KNITTING HOSIERY

Herbert Edward Woodcock, Hawick, Scotland, assignor to William Cotton, Limited, Loughborough, Leicestershire, England

Application April 14, 1944, Serial No. 531,011
In Great Britain January 1, 1943

5 Claims. (Cl. 66—89)

This invention concerns the manufacture, on a Cotton's Patent or other straight bar knitting machine, of a blank for a stocking or like article of footwear which has a foot resembling a French foot in that the foot top and the foot sole or bottom are knitted in one piece and the initial courses of the foot sole are united to the inner edges of the heel tabs. Hitherto the production of such blanks has necessitated the employment of two separate knitting machines; for example it is known to knit the leg and foot on one machine and then to separate the terminal courses of the high heel parts from the initial courses of the foot sole and (after a running-on process) to knit the heel tabs on to said terminal courses on a second machine, the inner selvedge edges of the heel tabs being subsequently linked to said initial courses. It is an object of the present invention to eliminate this subsequent step of linking and more particularly to provide a method and means whereby a blank, complete with heel tabs, is knitted on the one machine and the inner edges of the heel tabs are connected to the initial courses of the foot sole during manufacture.

The invention relates to the production of a stocking or like blank on a straight bar knitting machine, which comprises knitting the blank as far as the commencement of the heel, suspending knitting on a central group of needles, continuing to knit the heel tabs on needles beyond the ends of said groups, periodically transferring at least the inner margins of the heel tabs outwards, or otherwise widening them, while correspondingly increasing the number of inactive needles and ensuring that the additional inactive needles being at each end of said group, hold fabric, and subsequently resuming knitting of an instep and foot bottom on said fabric-holding needles.

In the exercise of this invention, in order that the needles that are progressively rendered inactive shall be caused to hold fabric, in the transfer operations at least one needle at each outer edge of the inactive group of needles may be stripped and previously-knitted fabric placed on it. Each transfer is preferably a two-needle transfer.

The foregoing and other features of the invention set out in the appended claims are incorporated in the machine which will now be described by way of example with reference to the accompanying drawings in which Figure 1 shows the heel portion of one stocking or the like according to this invention;

Figure 2 is a diagram illustrating the production of the blank therefor;

Figure 3 is a fabric diagram illustrating the sequence of courses in the production of one heel tab thereof;

Figures 4, 5 and 6 are views, similar to Figs. 1 to 3 respectively, illustrating a modified construction;

Figures 7, 8 and 9 are diagrams illustrating transfer operations herein described while

Figures 7a, 8a and 9a illustrate the movements of needles, points, and associated parts during said operations;

Figure 10 is a cross section, through a Cotton's Patent or other straight bar knitting machine according to this invention, showing the relevant parts;

Figure 11 is a cross section on a larger scale through the sinker head;

Figure 12 is a plan view, partly in section, of a part of the sinker head showing auxiliary presser mechanism;

Figure 13 is a front elevation of the needle bar, presser, points, and peaking blades, while

Figure 14 illustrates mechanism for operating said blades.

Referring primarily to Figs. 1-3, the leg of the stocking or like blank is knitted in the usual manner down to the last course before the commencement of the heel tabs *ht* (i. e. as far as the line *abba*), the said leg being fashioned in the usual manner if desired. The instep needles corresponding to the width *bb* are now rendered inactive but are caused to hold their loops while the knitting of heel tabs *ht* proceeds on needles *ab*. After a predetermined number of courses, preferably three, all the loops of the last course of each heel tab are transferred outwardly, preferably by two needles. This brings two additional selvedge needles into operation at each outer selvedge edge of the heel tabs; simultaneously the two needles at the inner edge of each tab are rendered inoperative but are caused to retain fabric. That is to say the width of the group of inactive fabric-holding needles is increased by four needles.

These operations are illustrated in Figs. 7 to 9 and 7a to 9a in which the needles are indicated at 10, the points of two wide sets of fashioning points at 11 (there being one point 11 for each needle of each group *ab*) two auxiliary points at the inner edge of each set of wide points at 111, sinkers at 12, and knocking over bits at 13. It will be understood that the outward transfer operations of the points 11 would normally re-

sult in two needles at the inner edge of each heel tab being stripped after the points 11 have been racked outwards two needle spaces, the inner selvedge loops of the two preceding courses being stretched sideways as in Fig. 7. The two inoperative needles might, on their ascent, pierce the fabric but the points 111 are employed to offer the fabric positively to them. These points 111 are capable of operation independently of the points 11. During the delivery, when the fabric is below the sinkers 12 but is held up by the knocking over bits 13, the points 111 descend at the plain side of their associated needles to pierce the fabric (Figs. 7 and 7a) and are then swung backwards into alignment with points 11 so that when the needles 10 ascend from below the knocking over bits 13 the active needles enter the loops on the points 11 while the two inactive needles pierce the fabric offered to them by the points 111. It is immaterial whether the points 111 pierce the inner selvedge loops or whether, as illustrated in Fig. 8, they pierce the fabric at some other point since either will result in fabric being taken up by the ascending inactive needles.

This three-course sequence of operations is repeated the appropriate number of times until the heel tabs *ht* are of the required length and until the number of inactive, fabric-holding, needles has been progressively increased, beyond that corresponding to the width *bb* to the required extent. It will be appreciated that although in Figs. 2 and 3 the inner margins of the heel tabs, whereat fabric is retained upon such added inactive needles, are shown as lying along the inclined lines *bc*, this has been done merely for the sake of convenience in illustrating the heel tabs and that the added inactive needles are aligned with the inactive needles of width *bb* and consist of or include the needles of width *ab*. It will further be appreciated that when, after the completion of the heel tabs, the inactive fabric-holding needles are reintroduced into activity, not only is the instep or top of the foot knitted on to the needles of width *bb* but the initial courses of the foot bottoms *fb* are knitted on to the inner edges of the heel tabs along the lines *bc*. The linking operation hereinbefore referred to is thereby obviated.

During the production of the heel tabs it is desirable to shape them at their outer selvedge edges. Therefore at a predetermined intermediate stage in the manufacture of the heel tabs, such as that indicated at *a' b'*, peaking blades 14 are brought into operation to exclude from the transfer operations of the points 11 the outer selvedge of each tab. These blades 14 operate in known manner as shields between the points and needles and thereby to prevent an outer group of each set of points 11 from operating. As a result, while the inner edge of each heel tab is inclined sideways the outer selvedge edge is not widened and, subsequent to the introduction of the peaking blades, the outer selvedge needle always remains the same and the progressive introduction of needles into activity at the outer selvedges ceases. These peaking blades may be taken out of operation before the finish of the heel tabs, in which case a few loose courses are then knitted at the end of each tab (as between *c'* and *c* in Fig. 3) in order to permit the terminal courses of the heel tabs to be linked together. If it is desired to obviate this linking then the peaking blades are retained in operation until the completion of the tabs but, at a stage indicated at *d* on Figs.

4, 5, and 6, they are progressively shogged outwards so that the needles knitting each tab are progressively reduced in number until all cease to operate and each heel tab is knitted to a point. It will be understood that the traverse of carriers that supply yarn for knitting the heel tabs is controlled by known mechanism, so that they supply yarn only to the required needles. Inner selvedge stops, and outer selvedge stops prior to the introduction of the peaking blades, are shifted in conformity with the racking of the points 11; after the peaking blades have been brought into operation the outer selvedge stops remain stationary.

15 The heel tabs being completed, thereafter all the inactive, fabric retaining, needles are restored to activity and the foot is knitted, the initial courses of the foot being shown at the bottom of Figs. 3 and 6.

20 In order to render the needles of width *bb* inactive at the commencement of the heel tabs, a special presser cam is brought into operation which does not bring the needle bar 110 sufficiently far forward to press in the normal manner.

25 The mechanism for effecting this modification in the pressing movements of the needles requires no illustration herein, but it may be mentioned that it is controlled by patterning mechanism indicated diagrammatically at 15 in Fig. 10.

30 Simultaneously, at each end of the presser bar 17 a portion thereof (17a, 17b) is moved forward so that notwithstanding their modified pressing movements the heel tab needles of groups *ab* press thereon. Furthermore these auxiliary

35 pressers 17a, 17b are racked outwards in conformity with the outward movement of the points 11 so that the width of the group of non-pressing needles is progressively increased while simultaneously the auxiliary pressers 17a, 17b are positioned to operate on the added active needles at the outer selvedge of the heel tabs.

40 One form of auxiliary presser mechanism is illustrated in Figs. 10 to 12. An actuating bar 18 is movable longitudinally in the sinker head 30 and is formed with two inclined portions 18a each co-operating with a ramp 19 on the respective auxiliary pressers 17a, 17b. This actuating bar 18 is given a considerable movement to the left, Fig. 12, into the position shown in chain

45 dotted lines. This movement of bar 18 is effected by rack and pinion mechanism 27 operated from a cam on the main cam shaft 16 through connections 28 and is controlled by the patterning mechanism 15. The said movement causes the auxiliary pressers 17a, 17b to be advanced to their operative position and brings the ramps 19 on to straight parts 18b of said bar 18. The length of each straight part 18b is such that the ramps 19 travel therealong and hold the pressers 17a, 17b forward during the subsequent outward racking of the latter. Two rack bars 20a, 20b, one for each auxiliary presser, are slidably mounted in the sinker head 30 and are arranged to be racked in opposite directions. The rack bar 20a, has a

50 dog 21a engaging in a slot 22a in the auxiliary presser 17a, while the bar 20b has a dog 21b engaging in a slot 22b in presser 17b. These bars 20a, 20b are racked in opposite directions, by means of rack and pinion mechanism indicated at 23, from a rack wheel 24 operated by a cam on the main cam shaft 16 through the medium of racking mechanism 25 controlled by the patterning device 15. The mechanism 23 is provided with a handle 26 whereby the auxiliary pressers 55 17a, 17b, may be wound inwards.

The two wide sets of points 11 are mounted on the usual point bars 31a, 31b supported from the top narrowing machine shaft 32, the fashioning movements being effected by known mechanism that requires no illustration or description. Each pair of points 111 is mounted at the inner edge of the associated wide set 11 and its narrow brass 111' is slidable in a housing 33 pivoted at 34 to the brass of said wide set so as to be capable of swinging about a horizontal axis into and out of alignment with the points 11. These swinging movements are effected by a horizontal rod 35 received in a vertical fork 36 of the top of each narrow brass 111', said rod 35 being supported by arms 37 from a rock shaft 38. The vertical movements of points 111, relative to points 11, are controlled by a horizontal rod 39 received on a fork 40 at the top of each narrow brass 111', said rod 39 being supported by arms 41 from a rock shaft 42. These rock shafts 38 and 42 are rocked under the control of the patterning mechanism 15 by cams on the main cam shaft 16; the rocking mechanism for shaft 38 is indicated at 43, 44, 45 and 46 and that for the shaft 42 is substantially identical, part of it being shown at 46'.

The peaking blades 14 are pivoted on the rock shaft 42 and are swung thereon into and out of operative position by ramps 47 which co-operate with pegs 48 carried by arms 49 projecting from said shaft, there being one ramp 47 and associated parts for each blade 14 because, as herein-after mentioned, the shaft 42 is divided into two parts. The ramps 47 are raised and lowered by mechanism, not shown, which is controlled by the device 15 and may comprise a truck lever and a cam on the cam shaft.

A form of mechanism by which the peaking blades 14 may be shogged outwards is diagrammatically illustrated in Fig. 14. The two parts of the rock shaft 42 are spring-biased inwards to press against opposite flanks of a stepped tongue 50 which is lowered step by step, to force said rods and blades apart, by rack and pinion mechanism 51 and a racking clawker 52 operated by any suitable means under the control of the device 15.

The yarn carriers and their operating mechanism are not illustrated since these parts are well understood. Finally, it may be added that while on the production of the heel tabs it is convenient to employ a 3-course sequence and a 2-needle transfer, yet the sequence may be more or less than 3 courses and/or the transfer over more or less than 2 needles; furthermore, while the widening is best effected by a loop transfer, it may be effected by any other means such for example as by increasing the carrier traverse to feed yarn to added needles.

I claim:

1. In a straight bar knitting machine of the type organized for the production of stocking or like blanks with heel tabs, said machine being equipped with needles, including a central group of instep needles, and with two sets of transfer points: the combination of means for temporarily suspending knitting operations on the instep needles while said needles continue to hold their loops and the knitting of heel tabs proceeds on needles beyond the ends of the group of inactive needles; means for operating the transfer points periodically to transfer progressively outwards at least the inner margins of the heel tabs; means for simultaneously making a corresponding increase in the number of temporarily-inactive needles that are comprised in the periodically widening central group; auxiliary points at the inner ends of the sets of transfer points; operating means for causing the auxiliary points to transfix the previously-knitted fabric at the plain side of the needles and to position it for reception by the needles that are progressively rendered inactive so that said needles thereafter retain fabric; and means for causing the needles of said widened group to resume knitting, after the production of the desired heel tab length, and to produce further fabric the first course of which is united to the inner margins of the heel tabs.
2. In a machine according to claim 1 having bearded needles, means for effecting said temporary suspension by preventing the appropriate needles from pressing.
3. A machine according to claim 1 being of the type having bearded needles and a presser therefor and in which relative pressing movements occur between needles and presser, having in combination means for modifying the pressing movements; auxiliary pressers for the heel tab needles; and means for bringing said auxiliary pressers into operation and for moving them outwards in conformity with the transfer operations to effect the aforesaid progressive increase in the number of temporarily-inactive needles.
4. A machine according to claim 1, having means mounting the auxiliary points for dipping and swinging movement independently of the transfer points.
5. A machine according to claim 1, having means for moving the auxiliary points across the line of needles from the plain side to the other side thereof while the needles are in a lowered position and for thereby offering fabric to be pierced by the rising needles.

HERBERT EDWARD WOODCOCK.
